UNITED STATES PATENT OFFICE.

OSCAR E. LAWSON, OF ALCESTER, SOUTH DAKOTA.

TERRET AND HITCHING-STRAP HOLDER.

SPECIFICATION forming part of Letters Patent No. 447,958, dated March 10, 1891.

Application filed July 5, 1890. Serial No. 357,920½. (No model.)

To all whom it may concern:

Be it known that I, OSCAR E. LAWSON, a citizen of the United States, residing at Alcester, in the county of Union and State of 5 South Dakota, have invented a new and useful Combined Terret and Hitching-Strap Holder, of which the following, taken in connection with the drawings, making part of same, is a full, clear, and exact description.

10 My invention is designed to form a simple and efficient means of securing the free end of the hitching-strap to harness when not used in tying the horse.

In the accompanying drawings, Figure 1 is 15 a side elevation of a terret constructed in accordance with my invention. Fig. 2 is an edge view of the terret with the spring B broken away.

I attain my object by means of the terret 20 A, having attached to the outside of its rounded surface, directly above the "washer-rim," a thin semicircular-shaped piece of spring steel or brass B, corresponding in width and outline to the terret used, and ex- 25 tending nearly or quite half-way around the terret. This piece of metal is secured to the base of the terret directly above the washer-rim, by means of a small rivet or screw C. It is also supported at or slightly below its center 30 by means of a band or loop D, cast solid with the terret and passing around said spring B, leaving a small opening between the spring and terret. At its upper end the spring B is bent or rolled out upon itself sufficiently to give 35 an easy entrance for the strap. From the center D up the surfaces of spring and terret fac- ing are creased or corrugated lengthwise to enable the spring to get a firmer "grip" on the strap when in place. The spring B is shaped 40 and tempered, so that when in position the ends press firmly against the terret while the

center, at D, tends outward. The strap, being admitted a convenient distance from the free end into the opening or "mouth" of spring and terret, is pressed in place with the 45 fingers and, without tying the strap, the spring is intended to be sufficiently stiff to hold it automatically.

Importance is attached to the form of the spring B, as by having the same normally in 50 close contact with the outer face of the terret at a point near the free end of the spring, the strap will be prevented from accidental displacement, while the more open space between the end of the spring and the part D allows 55 the strap a limited movement. The corrugations upon the outer face of the terret serve, in conjunction with the spring B, to more securely retain the strap against displacement.

What I claim as my invention, and desire 60 to secure by Letters Patent, is—

As an improved article of manufacture, the herein-described combined terret and hitching-strap holder, the same consisting of the terret A, the spring-arm B, secured to the 65 outer face of the terret by means of a rivet C passed through the lower end of the arm, the upper end of the arm being normally in close contact with the terret, with a space intervening between the body of the spring and 70 the terret, the outer face of the terret upon the side adjacent to the arm being provided with longitudinal corrugations, as described, and a retaining-hook D, integral with the terret and serving to retain the arm B in position, substantially as described, and for the 75 purpose specified.

OSCAR E. LAWSON.
